UNITED STATES PATENT OFFICE.

ALEXANDRE AMBERT, OF LYONS, FRANCE.

PERMANENT WAY OF RAILWAYS OR TRAMWAYS.

SPECIFICATION forming part of Letters Patent No. 728,652, dated May 19, 1903.

Application filed September 18, 1902. Serial No. 123,926. (No model.)

To all whom it may concern:

Be it known that I, ALEXANDRE AMBERT, engineer, a citizen of the French Republic, residing at 19 Quai Yair, Lyons, France, have 5 invented certain new and useful Improvements in the Permanent Ways of Railways or Tramways, of which the following is a specification.

This invention relates to the permanent 10 ways of railways and tramways, and has for its object to increase the stability of such permanent way whatever may be the kind of railway or tramway and form of rails.

According to this invention the rails are 15 secured in position by means of elastic supports and of elastic keys or wedges forced under great pressure between the rails and the said supports. The keys or wedges owing to their elasticity and that of the support 20 cannot become loose, however great may be the shocks caused by the vehicles running thereon.

In order that my invention may be clearly 25 understood, I will describe it with reference to the accompanying drawings, in which—

Figures 1 and 2 show in section and elevation my invention applied to a suspended rail-joint of Vignole rail. Fig. 3 shows application to a grooved rail of the Broca type. Figs. 30 4 and 5 show in section and elevation an application to a Vignole rail for its connection to metallic sleepers. Fig. 6 is another construction of this application. Figs. 7 and 8 show another kind of connection. Figs. 9 35 and 10 show the invention applied to the connection of a rail with a metal sleeper by means of a cross-shaped block. Fig. 11 shows a rail connection with a metal sleeper by means of a hooping device.

In applying my invention to a suspended rail-joint, Figs. 1, 2, 3—that is, a joint between two rail ends between sleepers—the adjacent rail ends d d' are held in a support or clamp a , of highly-elastic metal, having clips 40 extending over the flanges of the rails, and between the under side of the said flanges and the support elastic keys or wedges b c are driven with great force. The rail-flange may be secured by one key or wedge or many keys

or wedges. The support a may be made in 50 one or in two or more parts. If made in parts, each part is provided with upper and lower turned-in portions, between which the rail-flange is secured by a key or wedge or keys or wedges, as hereinbefore described. The 55 said support may be strengthened by ribs. The driving in of the keys or wedges may be effected by a screw-jack, hydraulic pressure, or other suitable means. In order to obtain a more powerful grip, the support may be 60 heated before being placed in position. For connecting the rails to metal sleepers, Figs. 4, 5, 6, the support a embraces the rail d and the sleeper e , Fig. 6, or embraces only the rail and is riveted to the sleeper, or it may be 65 made integral with the sleeper, Figs. 4 and 5. In this case the support may be only a hook g , Figs. 7 and 8. The fastening of the rail to the support is effected by driving a key or wedge or keys or wedges forcibly between the 70 support and the under side of the rail-flange, as hereinbefore described with reference to the fastening at the suspended joint. The required canting of the rail can be obtained by giving a suitable incline to either the key 75 or wedge or one of the keys or wedges or to the support or to the sleeper. In the application shown in Fig. 6 the canting is obtained with an inclined key b . In this arrangement the support a embraces the sleeper e and the 80 rail d . In the arrangement shown in Figs. 4 and 5 the canting is obtained by giving a suitable incline to the support a , riveted on the sleeper e .

Figs. 7 and 8 show an application with 85 hooks g riveted on the sleeper, and Fig. 9 with a cross-shaped block—that is to say, a block being grooved for embracing the rail and being grooved in a perpendicular direction for embracing the sleeper. 90

Fig. 11 shows a rail connected with a metal sleeper by means of a hooping device.

Having now particularly described and ascertained the nature of my invention and in what manner the same may be performed, 95 what I claim is—

In a rail-joint for railways the combination with the rails of an elastic clamp arranged

beneath the meeting ends of the rails and embracing the upper sides of the rail-flanges, and an elastic key or wedge forced under great pressure between said clamps and the bottom of the rails, said key or wedge being disposed longitudinally relatively to the rails, substantially as described.

In testimony whereof I have hereunto set my hand in presence of two subscribing witnesses.

ALEXANDRE AMBERT.
